UNITED STATES PATENT OFFICE.

NASON BURNHAM, OF NORWALK, OHIO.

IMPROVEMENT IN SPRING-BALANCES.

Specification forming part of Letters Patent No. 35,869, dated July 15, 1862.

To all whom it may concern:

Be it known that I, NASON BURNHAM, of Norwalk, in the county of Huron and State of Ohio, have invented a new and improved article of manufacture in the shape of an Improved Spring-Balance, an article which may also be used as a pressure-indicator on steam-boilers; and I do hereby declare that the following is a full and exact description thereof, reference being had to the accompanying drawings, which form a part of this specification.

The accompanying drawings represent my improved spring-balance as being combined with the dome of a steam-boiler for the purpose of being used as a pressure-gage, Figure 1 being a side view, and Fig. 2 a section of the same.

My improved spring-balance is composed of a casing, A B C, a graduated rod, *d*, a volute spring, *e*, and a disk, *f*, arranged with each other in the manner represented in Fig. 2.

The improvement in said spring-balance over all other articles employed for the same purpose consists in the use in said balance of

a volute spring instead of a helical spring, practical experiment having fully demonstrated that a volute spring possesses much more strength in proportion to its weight than any other form of spring, and also that this said form of spring expands and contracts under the influence of various degrees of pressure with a more reliable and uniform rate of movement.

What I claim as my invention, and desire to secure by Letters Patent as a new article of manufacture, is—

A spring-balance in which a volute spring (of the form represented in the drawings) is employed substantially in the manner herein set forth.

The above specification of my improved steam-pressure gage or spring weighing-balance signed and witnessed this 17th day of February, 1862.

NASON BURNHAM.
